RUFUS W. RUSSELL, OF LOS ANGELES, CALIFORNIA.

COMBINATION CAMP-KIT AND TABLE.

1,286,118.

Specification of Letters Patent. Patented Nov. 26, 1918.

Application filed July 1, 1916. Serial No. 107,476.

To all whom it may concern:

Be it known that I, RUFUS W. RUSSELL, a citizen of the United States, residing at Los Angeles, in the county of Los Angeles and State of California, have invented a new and useful Combination Camp-Kit and Table, of which the following is a specification.

My invention relates to camp kits. The 10 principal object of the invention is to provide a kit in which various articles may be packed for the purpose of transportation, this kit being readily opened up to form a table in camp.

15 The invention has a spacial utility in connection with an automobile, as food, dishes, and the like may be packed therein and readily transported both on the automobile and by hand when in the woods, the same 20 kit being utilized to form a table in camp.

For the purpose of accomplishing the above objects certain novel structure is employed as will be more fully set forth hereinafter.

25 Referring to the drawings, which are for illustrative purposes only:

Figure 1 is a perspective view of the camp kit arranged for transportation.

Fig. 2 is a cross section through one of 30 the leg compartments of the camp kit.

Fig. 3 is a perspective view of the camp kit arranged as a table.

As illustrated in the drawings, the kit consists of a box 11 which is provided with 35 a handle 12, this handle being arranged on what may be called the side of the box, the words, "side", "top" and "bottom", etc., as used herein referring to the box in the position as shown in Fig. 3, or in the position 40 when used as a table.

The box arranged as shown in Fig. 1 forms a kit approximately the size of an ordinary suit case, and this kit may be placed upon the running board, or on the trunk 45 rack of an automobile, or it may be transported in various ways as will be evident from the drawing.

Secured in the box 11 near either end thereof are partitions 13, these partitions 50 separating the central portion of the box 14 from two narrow leg compartments 15 located in either end thereof. The leg compartments 15 are each provided with a cover 16 secured to the body of the box by hinges 55 17, and provided with a hasp 18 by which

they can be held in the closed position as shown in Fig. 1, the covers 16 hanging down in their open position as shown in Fig. 3 when the kit is used as a table. Secured at either end of each of the leg compartments 60 15 is an upper leg pivot 19 and a lower leg pivot 20, these pivots being located as shown in Fig. 2 at the extreme ends of the box, and one of them above the other. Pivoted on each of the pivots 19 and 20 are legs 65 21, these legs consisting of two upper portions 22 which are held together at their lower end by a strap 23 which entirely encircles them. Sliding between the legs 22 is a lower movable leg 24. Secured in and 70 passing through the leg 24 is a bolt 25 having a thumb nut 26 which operates on a washer 27 which overlaps the upper legs 22 and allows the lower leg 24 to be secured in adjustable relationship therewith in such 75 a manner that the height of the legs can be varied to suit any irregular contour of the ground on which it is desired to set the table.

Pivoted on hinges 30 on the upper edges 80 of the sides of the box are two leaves 31, these leaves closing over the top of the box when arranged as shown in Fig 1, and being secured by means of catches 32 which engage pins 33 secured in the edges of the leaves 31. 85 Sliding in the upper portion of the leg compartments 15 are slides 34, these slides being adapted when pulled out to support the leaves 31 to form shelves on either side of the kit. Extending across the top of the box is 90 a cross bar 35, this cross bar fitting into a socketed opening 36 on either end of the box, and having lids 37 secured by hinges 38 on either side thereof. The lids 37 fold down against the partition 13 and form a flush 95 surface with the top of the box when closed. Finger openings 39 are placed therein so that they can be readily opened. The leaves 31 and the lids 37 with the cross bar 35 form an approximately continuous and unbroken 100 flat surface which may be used in the manner of any other table, and the central compartment 14 provides a space in which dishes of food may be stored, ready access being had to this space by lifting either of the lids 37 by means of the finger hole 39.

The method of operation of the invention is as follows:

The articles to be transported are placed in the compartment 14, the lids 37 are put in 110

place, and the leaves 31 are folded over and secured by the catch 32. The slides 34 are pushed in until approximately flush with the outer surface of the box. The legs are folded 5 up into place, and the covers 16 are secured by means of the hasp 18. The kit is then in the condition shown in Fig. 1, and may be readily transported.

When it is desired to convert the kit into 10 a table the covers 16 are released by releasing the hasps 18, and the legs are folded down into the position shown in Figs. 2 and 3, these legs being adjusted to suit the height of the ground. The catch 32 is then released 15 and the slides 34 are pulled out so that the leaves 31 are supported in the position shown in Fig. 3.

While I have described one particular use 20 for my invention, *i. e.*, its use as a camp kit, it has various other uses, and may be used by commercial travelers or salesmen for the purpose of transporting and exhibiting their wares, serving in this case as a sample or 25 selling case. All such uses are obviously within the scope of my invention, which is to be limited only by the annexed claims.

I claim as my invention:—

1. A camp kit comprising a box, legs on 30 which said box may be supported, a pair of leaves hinged to said box in such a manner that they may be folded in to close the top of the box, a cross bar extending across the top of said box, a pair of lids one on either side of said cross bar, said lids each being 35 hinged to said cross bar, and adapted to close the top of said box, and means for supporting said leaves in their open position to form shelves extending outwardly from the side of the box.

40 2. A camp kit comprising a box, walls forming narrow leg compartments at either end of said box, said compartments being open on the bottom, legs pivoted in said compartments upon which said box is supported, a 45 pair of leaves hinged to said box in such a manner that they may be folded in to close the top of the box, a cross bar extending across the top of said box, a lid hinged to said cross bar and adapted to close the top 50 of said box, and means for supporting said leaves in their open position to form shelves extending outwardly from the side of the box.

55 3. A camp kit comprising a box, walls forming narrow leg compartments at either end of said box, said compartments being open on the bottom, legs pivoted in said compartments upon which said box is supported, a pair of leaves hinged to said box in such a 60 manner that they may be folded in to close the top of the box, a cross bar extending across the top of said box, a pair of lids one on either side of said cross bar, said lids each being hinged to said cross bar and adapted 65 to close the top of said box, and means for

supporting said leaves in their open position to form shelves extending outwardly from the side of the box.

4. A camp kit comprising a box, walls forming narrow leg compartments at either 70 end of said box, said compartments being open on the bottom, two upper leg pivots each located near the top of one end of one of said leg compartments, two lower leg pivots each located near the bottom of the 75 other end of said leg compartments, four legs each leg being pivoted on one of said pivots and so formed that it may be folded into one of said leg compartments, the leg pivoted on the upper leg pivot occupying the upper part of said leg compartments and the leg pivoted on said lower leg pivot occupying the lower part of said leg compartment when said legs are folded into 80 said compartment, a pair of leaves hinged to said box in such a manner that they may be folded in to close the top of the box, and means for supporting said leaves in their open position to form shelves extending outwardly from the side of the box. 90

5. A camp kit comprising a box, walls forming narrow leg compartments at either 95 end of said box, said compartments being open on the bottom, two upper leg pivots each located near the top of one end of one of said leg compartments, two lower leg pivots each located near the bottom of the other end of said leg compartments, four legs each leg being pivoted on one of said 100 pivots and so formed that it may be folded into one of said leg compartments, the leg pivoted on the upper leg pivot occupying the upper part of said leg compartment and the leg pivoted on said lower leg pivot occupying the lower part of said leg compartment when said legs are folded into said compartment, a pair of leaves hinged to 105 said box in such a manner that they may be folded in to close the top of the box, a cover adapted to drop into the top of the box for the purpose of closing the top of the box when said leaves are open, means for supporting said cover in the top of said box, and means for supporting said leaves in their open position to form shelves extending 110 outwardly from the side of the box. 115

6. A camp kit comprising a box, walls forming narrow leg compartments at either end of said box, said compartments being open on the bottom, two upper leg pivots 120 each located near the top of one end of one of said leg compartments, two lower leg pivots each located near the bottom of the other end of said leg compartments, four legs each leg being pivoted on one of said 125 pivots and so formed that it may be folded into one of said leg compartments, the leg pivoted on the upper leg pivot occupying the upper part of said leg compartment and the leg pivoted on said lower 130

- leg pivot occupying the lower part of said leg compartment when said legs are folded into said compartment, a pair of leaves hinged to said box in such a manner that they may be folded in to close the top of the box, a cross bar extending across the top of said box, a lid hinged to said cross bar and adapted to close the top of said box, and means for supporting said leaves in their open position to form shelves extending outwardly from the side of the box. 7. A camp kit comprising a box, walls forming narrow leg compartments at either end of said box, said compartments being open on the bottom, two upper leg pivots each located near the top of one end of one of said leg compartments, two lower leg pivots each located near the bottom of the other end of said leg compartments, four legs each leg being pivoted on one of said pivots and so formed that it may be folded into one of said leg compartments, the leg pivoted on the upper leg pivot occupying the upper part of said leg compartment and the leg pivoted on said lower leg pivot occupying the lower part of said leg compartment when said legs are folded into said compartment, a pair of leaves hinged to said box in such a manner that they may be folded in to close the top of the box, a cross bar extending across the top of said box, a pair of lids one on either side of said cross bar, said lids each being hinged to said cross bar and adapted to close the top of said box, and means for supporting said leaves in their open position to form shelves extending outwardly from the side of the box. 25 30 35

In testimony whereof I have hereunto set my hand at Los Angeles, California, this 23rd day of June, 1916.

RUFUS W. RUSSELL.
